UNITED STATES PATENT OFFICE.

ANTONIO CHIARELLI, OF NEW YORK, N. Y.

PROPELLED MECHANISM FOR AIR NAVIGATORS.

Application filed May 29, 1925. Serial No. 33,615.

This invention relates to improvements in the art of aerial navigation, particularly to means which may equally well be used to propel and manoeuvre lighter than air and heavier than air craft, such as dirigibles, balloons, aeroplanes, or the like.

The new propelling and manoeuvring system can also be applied to marine craft and vehicles to be operated on land.

It is the principal object of the invention to provide a novel propelling and manoeuvring system for air craft of all descriptions allowing a ready change in the direction of flight, in the deviation from the horizontal, and greatly facilitating landing and ascending operations.

A further object of the invention is the provision of a propelling and manoeuvring system for aerial and other craft including a plurality of motors, each of which can be coupled or uncoupled from the others, if repairs, etc., require this.

A still further object of the invention is the provision of a novel propelling and manoeuvring system for air craft, or the like, equipped with sliding wings and a plurality of motors for operating the same, which are encased in a common carrier of trapezoid form or a skeleton frame to which cars or gas bags, etc., of substantially cigar shape may be attached or suspended therefrom.

The invention also embraces means for manoeuvring the propellers to steer the air craft, and means for allowing a change in the elevation.

These and other objects and advantages of my invention will become more fully known as the description thereof proceeds, and will then be specifically defined in the appended claims.

In the accompanying drawing forming a material part of this disclosure:

Fig. 1 is a side elevation of an airship constructed according to the present invention.

Fig. 2 is an end view thereof.

Fig. 3 is a diagrammatic view of the arrangement and construction of the propelling means and their operating elements.

Fig. 4 is a fragmentary sectional view on line 4—4 of Figure 3.

Fig. 5 is a top plan view of an air-ship constructed according to the present invention.

Fig. 6 is a sectional side elevation of the propelling means on an enlarged scale. 55

Fig. 7 is a plan view of the operating machinery.

Fig. 8 is a modification illustrating the employment of the improved propelling and manoeuvring means to a lighter than air 60 balloon.

As shown in Figures 1 and 2, as one example of executing the invention in practice, the body 10 of an air-ship of suitable material and shape, is adapted to contain 65 the operating machinery and has attached thereto a nose 11 and tail 11' in the form of air or gas filled balloonettes having pointed outer ends.

To the body 10 a plurality of cabins 12 70 and 13, having windows 14, are attached or suspended therefrom, laterally disposed to said body and having a substantially cigar-shape such as for instance, used in the construction of air-ships of the Zeppelin type. 75

The air-ship is equipped with a plurality of motors 15 which can be coupled to the propeller shaft 16 by suitable couplings 17 adapted to be operated by suitable shifting levers 18. 80

The propeller shafts rotates drums 19 about ball bearings 20, to which the shaft 23 is eccentrically arranged, said bearings having attached thereto a propeller wing or blade 21 extending out of the drum 19 and 85 having a curved extreme outer end.

This wing or blade is slidably guided through an opening in the drum on bearings 22 and extends more or less, out of the drums during the eccentric displacement of the element carrying the wing about the shafts 23. 90

The outer ends of shafts 23, within shafts 16, extending from its eccentric collar 24 and journally projecting or pivoted into drums 19, carry gears 25 in mesh with a rack 95 26 secured to the frame or body 10 by brackets 27.

The steering is effected by means of a pair of hand wheels 28 and 29, on a transverse shaft 30, the outer ends of which are in engagement with the racks 26, while a coupling consisting of the members 31 and 32, allows a coupling of both wheels, if the ship is to be propelled in a straight forward, backward, upward or downward direction. 100 105

The deviations from the horizontal are

controlled by a motor 33 carrying wing drums and wings 34 and 35, of the above described construction having movable shafts carrying gears, at their outer ends in engagement with the racks 36 and 37.

The entire structure standing under the influence of a solenoid 38 which is operated by floats 39 in a water containing conduit 40, provided at both sides of body 10.

10 The racks 26 can each be displaced by the operation of hand wheels 41 on shafts 42.

A rudder 43 can be used in the ordinary well-known manner to assist the steering of the craft by means of the propellers.

15 As shown in Figure 8, a balloon 44 having a gondola 45 attached thereto, has mounted on top of it a skeleton, a frame 46 carrying the motor 47 and on the shafts 48 thereof. Outside of the frame 46, the propeller drums 20 and wings 49 and 50 are mounted.

The shafts 51 thereof, are journaled, or pivoted in the drums in the above described manner, and carry gears 52 attached thereto in mesh with gears 53 on a shaft 54 on which

25 is also secured a bevel gear 55 in mesh with a bevel gear 56 on a vertical shaft 57 carrying at its lower end in the gondola, suitable operating means.

The device operates as follows:

30 Upon the starting of the motors with the coupling members 31 and 32 coupled, the craft will be propelled forward, backward, upward and downward in a straight line according to the direction of flight. If a ste

35 ring at a deviation from the straight line is desired, the rudder 43 is thrown into its appropriate position and the members 31 and 32 are uncoupled, while the racks are given the desired and appropriate inclination to

40 the body by the operation of shafts 42 by hand wheels 41, as their rear ends are engaged with said racks. On account of the cushioned arrangement, of the gear shafts 23, these shafts will turn in the corresponding 45 direction.

A deviation from the horizontal either at the front or the rear of the craft is effected by the proper energization of solenoid 38 which may be controlled at will or by the 50 floats 39 in the water contained in conduits 40 which shift the center of gravity to one or the other direction.

It will be clear that air craft equipped with my novel propelling and manœuvring system can be steered and propelled in a suitable manner.

It is to be understood that the oar-shaped propeller wings sliding in and out of their respective drums, will act on the air or water 60 to concentrate the propelling and driving force wherever most desirable and required.

An ascent and landing will be quickly and easily effected by a corresponding manipulation of the propeller wings and motors or 65 solenoid.

If any of the motors goes dead and needs repairing this can quickly be done without interruption of the flight by operation of the respective clutch to cut the motor out of engagement with the other motors.

70 While I have shown a body having a trapezoid form, it will be clear that any other suitable form may be used. The passenger carriers may also be used as freight, mail, etc., carriers, especially when used in combination with bags filled with helium gas.

75 My device may be equipped with the usual elevators and other equipment which are generally used for propelling air-ships.

80 While I have illustrated and described one example of the many ways to construct my novel propelling and manœuvring system, it will be clear that I may use individual mechanism to manipulate each propeller and that such changes may be made in the general arrangement and in the specific construction of the minor details, as fall within the scope of the appended claims without departure 85 from the principle involved.

Having thus described my invention, what I claim as new, and desire to secure by Letter Patent, is:

1. A propelling and manœuvring system for airships comprising a trapezoid body, a gas bag in front and rear of said body, a plurality of passenger and freight carriers supported by said body, a plurality of motors in said body, means for coupling and uncoupling any of said motors from the others, a plurality of drums in the shafts of said motors, a wing in each drum adapted to slide out and into said drum, gear shafts journaled in the drum, and means for allowing a displacement of these last shafts in one and the other direction to steer the craft at any desired angle to the horizontal, and a means for carrying a load attached to said body.

2. In a propelling and manœuvring system for air craft, a shaft, a plurality of drums attached to the same, a ball bearing in each of said drums eccentrically arranged to said shaft, a gear shaft, an eccentric collar on said gear shaft, means for journaling said gear shaft, and a propeller blade on said eccentric collar adapted to slide out of and into its drum, and a means for allowing a steering of the craft by said propeller wings.

3. In an air craft propelling and manœuvring system, a plurality of motors, couplings to couple and uncouple any one of said motors from the others, means for operating said couplings, shafts connected to said motors, drums on said shafts, a wing in each drum adapted to move out and into the same, journaled shafts in said drums, outer shafts, gears on the outer ends of said outer shafts, racks with which said gears are in mesh, and means for displacing said racks for allowing a steering of the air craft in

one or the other inclination to the vertical in a horizontal plane.

4. In an air craft propelling and manœuvring system, a plurality of motors, propellers on each side of the craft, journaled displaceable shafts for said propellers, and means for displacing said propellers in one and the other direction for steering the craft, a rudder for assisting in the propeller

10 steering, and a means for connecting the propellers on both sides of the craft to assist the steering by the rudder in a straight line.

5. In an air craft propelling and manœuvring system, a body, water conduits on said body, floats in said conduits, a solenoid actuated by said floats to shift the center of gravity, and a motor and propeller wings for allowing a steering of the craft at an 20 angle to the horizontal toward above or below.

6. In a balloon having a gondola suspended from its skeleton, a frame carried at the top of said skeleton, a shaft journaled in 25 said frame, a motor driving said shaft, drums driven by said motor propeller wings rotated by said drums for propelling said balloons, and a means for allowing a steering of the same by said propeller.

30 7. In a balloon having a gondola suspend-

ed from its skeleton, a frame carried at the top of said skeleton, a motor having its shaft journaled in said frame, drums on said shaft, a propeller wing in each drum sliding into and out of the same, journaled shaft 35 therein, eccentrically displaced, gears on the extreme outer ends of said last-named shaft, and a means for allowing a steering of said balloon by said propellers.

8. A propelling and manœuvring system 40 for air craft, comprising a trapezoid skeleton frame, two gas bags having pointed outer ends secured to said frame, a pair of cabins suspended from said frame having windows, a system of propellers in said 45 frame, couplings for allowing a coupling and uncoupling of any of the motors of the system from the rest thereof, levers for the operating of said couplings, a pair of rack bars, supports on said frame on which said 50 rack bars are normally supported, a plurality of the propeller wings operated from said motors to drive the craft in any direction, and means for allowing an engagement of said rack to displace the propellers in any 55 direction to steer the craft.

In testimony whereof I have affixed my signature.

ANTONIO CHIARELLI.
